 B. F. Sturtevant Company, Hyde Park, Mass.,
 a corporation of Massachusetts

Application March 12, 1931, Serial No. 521,997

11 Claims. (Cl. 236—38)

The present invention relates generally to heating ventilators and particularly to unit heating ventilators and methods of operating the same wherein the heating of air passing there-

5 through is thermostatically controlled.

The objects of the present invention are to provide a unitary structure which shall embody not only the heating and ventilating mechanism but also the control devices therefor, which shall be 10 simple in construction and which shall operate with certainty and accuracy to maintain the desired conditions.

With these and other objects in view as will hereinafter be apparent to those skilled in the 15 art, the present invention consists in the devices and combinations of devices and method of operation hereinafter described and more particularly defined in the claims.

The invention in its preferred form is illustrated in the accompanying drawings in which Fig. 1 is a front elevation, partly in section, of the unit heating ventilator; Fig. 2 is a sectional view along the line 2—2 of Fig. 1 showing also the mode of installation of the unit heating 20 ventilator; Fig. 3 is a side elevation of the unit ventilator; Fig. 4 is a view of the thermo-regulating device in front elevation, and Fig. 5 in vertical section along the line 5—5 of Fig. 6; Fig. 6 shows the device in side elevation; Fig. 7 is a schematic 25 diagram of the circulation of air within the unit heating ventilator shown in a front elevation, partly in section; and Fig. 8 is a side elevation 30 of a friction clamp utilized in a modification of the preferred embodiment of the invention.

The construction shown in the drawings comprises a ventilator casing having suitable inlets 35 for air, means of filtering the air, motor driven fans for forcing the air through the ventilator, means for heating the air during its passage, means for by-passing the air around the heating 40 means, thermo-regulating means for actuating the means for by-passing the air around the heating means, and an outlet in the casing for the emission of the air.

In the ventilator illustrated in the drawings, a 45 casing 1 contains heating elements 3 with extended surfaces 5, over which currents of air are forced upwardly by the pair of squirrel cage fans 7 borne by and driven by the motor 9 mounted on the flexible suspensions 11. The air so upwardly forced by the fans is drawn through the filter 13 from the chamber 15 which is provided 50 with two inlets. One, 17, of these inlets permits the passage into the chamber 15 of the outdoor air from the usual duct or passage 19 through

the wall 21, while the other, 23, of the inlets permits the passage into the chamber 15 of the air of the room wherein the unit heating ventilator is situated.

The control of the admission of air through one inlet or the other is by means of a hand actuated damper 25, the spring ensemble 27 precluding any intermediate position of the damper and thereby preventing the possibility of the passage of air directly from the outdoors into the room.

The filter 13 consists of a long, shallow box-like structure with wire netting forming its bottom and top, between which is held oily iron or steel fibres through which air passes fairly freely under the suction created by the fans.

The squirrel cage fans 7 are of the double intake type and have spiral casings 29 with inlet openings 31 at their sides and vertical tangential discharge through outlets 33 to the heating elements 3.

For the purpose of controlling the amount of heat imparted to the air passing through the apparatus, two movable shutters or dampers 35 are provided, which are actuated by a thermo-regulator shortly to be described. When the 25 shutters are in the positions shown in full lines in Fig. 2, all of the air from the fans passes over the heating elements 3 and the maximum heating effect is produced, but when the shutters are in the position shown in dotted lines in Figs. 30 2 and 3, all of the air from the fans is by-passed around the heating elements through the passage 37, and the minimum, that is, substantially no heat whatsoever is imparted to the air. In any intermediate position of dampers or shutters 35, a portion of the air passes over the heater and a portion is by-passed so that only a moderate amount of heating of the air discharged through the casing outlet 39 is effected. By proper adjustment of the shutters 35 any desired temperature of air can be obtained.

The position of the shutters 35 is automatically controlled by thermostatic devices responsive to the temperature of the room wherein the heating ventilator is located. Heretofore such devices 45 have been located at some distance from the ventilator and electrical or other connections have been provided between these devices and the ventilator. According to the present invention the thermostatic device is located on or within the 50 casing of the ventilator and is directly connected mechanically with the damper or shutters 35.

The thermo-regulating device shown in the drawings is of a well known type. Its construction and mode of operation may be understood 55

by reference to Figs. 4, 5 and 6. Briefly, it comprises a hermetically sealed metallic bellows 51 containing a substance such as ether, whose vapor pressure increases rapidly with the temperature 5 and thereby expands the bellows. Through suitable connections between the bellows and the shutters, this expansion is effective to impart closing movements directly to the latter, while reverse movement is secured by means of a spring 10 when the internal pressure decreases, following a reduction in temperature.

The bellows 51 of general elliptical cross-section as shown in dotted line in Fig. 4 and in full line in Fig. 5, is mounted within a box or chamber 15 53 secured to the end wall of the casing. Air may pass freely through the box or chamber from the air inlet grille 54 in the casing wall, to and through the outlet 55 into the interior of the casing. The bellows is mounted in the chamber 20 by means of a cage 57 having a back plate to engage the back of the bellows and supporting side straps 59 spaced around and extending from said plate with their free ends bent over and secured by screws 61 to the supporting plate 63 25 upon which the parts of the device are mounted and which in turn is secured to the end or side wall 65 of the casing by means of the screws 67.

Secured to the front face of the bellows structure by means of short posts 69 is the pressure 30 plate 71 of the same general elliptical shape as the bellows but slightly smaller. When the bellows expand, due to a rise in temperature and the vaporization of the ether or other liquid contained therein, the plate is pushed outwardly, that 35 is, to the right as shown in Fig. 6, in opposition to the spring 73 and into a recess or opening in the supporting plate. Upon reduction of temperature, the spring forces the plate inwardly to collapse the bellows. The spring 73 rests at its 40 inner end upon the bellows plate 71 and at its outer end upon the cross-head 75 having recesses at its top and bottom to receive the fixed horizontal posts or supports 77 integrally formed with the supporting plate 63 whereby the cross-head will be guided in its inward and outward 45 movement. A hub or stem 79 on the cross-head holds the spring 73 from displacement.

The adjustment of the compression spring 73, 50 in order to secure the operation of the regulator at the desired temperature, is obtained by means of the threaded stem 81 upon which the cross-head is mounted. This stem carries the collar or shoulder 83 and is extended without threads 55 through a bearing sleeve 85, terminating in a square end 87 to receive an adjusting key. The bearing is carried by a six-sided plate 89 secured to the ends of the posts 77. A screw 91 passing through the end wall 65 of the casing enters the extension 93 of the plate and affords additional 60 support for the same and for the regulator.

The expanding and contracting movements of the bellows under the changes of temperature are transmitted to the shutters 35 to close and to open the same to a greater or less extent by means 65 of the following mechanism. Secured to the bellows plate 71 at each side of the compression spring 73 are the threaded studs 95, each having a horizontal V-notch at its outer end and with which engages the knife edge 97 on the bell-crank lever 99, actuating the same in a counter-clockwise direction, as viewed in Fig. 6, upon a rise in temperature and outward movement of the stud. Positive movement in the reverse direction is imparted to the bell-crank lever by 70 means of the angle plate 101, having its base

plate 103 through which the stud 95 passes clamped between the adjusting nuts 105. This plate 101 is provided at its front or right hand end, as viewed in Fig. 6, with a V-notch oppositely disposed to the V-notch on the end of the adjacent threaded stud, and in this V-notch on the plate is a second knife edge on the bell-crank lever 99. 5

The above described arrangement of notches and knife edges is duplicated with the other 10 threaded stud, so that the movements of the bellows plate will be imparted to the bell-crank lever without liability of tilting or binding of the plate or bellows or of the bell-crank lever. Thus the bell-crank lever will be positively actuated 15 in one direction or the other upon changes in temperature and the consequent movement of the bellows to adjust the shutters 35.

The bell-crank lever 99 is composed of two parts, one part, indicated generally at 107, carrying the connections to the shutters, and the other part, which is indicated generally at 109, which is of irregular shape, bearing the knife edges and the supporting devices for the lever, the two parts being united by means of screws 25 111.

The bearings for the irregular member 109 of the bell-crank lever comprise at one end a pivot pin 113 fixed in the bracket or projection 115 from the supporting plate 63, and at the 30 other end a knife edge on the depending portion of the fixed angle bracket 111, which engages with the notch on the lever. This portion of the bell-crank lever carries at its lower end the pivoted link 119, which in turn is connected at 35 its lower end to the arm 121, pivoted at one end upon the supporting plate 63 and connected at its other end to the closed spring 123, the upper end of which is adjustably connected to the fixed bracket 125. The action of the spring 40 supports the bell-crank lever with its notch in engagement with the knife edge on the bracket 111, with the desired pressure determined by the adjustment of the spring, the spring expanding and contracting as required to permit movement of the bell-crank lever under the action 45 of the bellows.

Motion from the free end of the bell-crank lever is transmitted to the shutters 35 by means of the link 127 connected at its upper end to the 50 arm 129 upon the rock-shaft to which one of the shutters is attached, a separate link connection 131 to the rock-shaft for the other shutter causing simultaneous operation thereof.

In order to protect the regulator and its sensitive bellows from heat and cold within the casing, an insulating lining 133 of suitable material is applied to the inner wall of the box or chamber 55 53.

To permit hand control of the shutters, a 60 handle 135 is provided, fixed upon the rock-shaft of one of the shutters at the opposite end from the connection to the regulator, and to insure the shutters being held in the desired adjusted position, there is provided the friction 65 clamp, indicated generally at 137 and shown in detail in Fig. 8. During normal operation of the apparatus, while the regulator is in control, the clamping members 139 are loosely held by the screws and nuts 141 so that little if any resistance is offered to movement of the shaft by the regulator. When, however, it is desired to control the shutters by hand, the nuts 141 will be tightened to cause the clamping members to bear upon the hub 143 on the shaft with suffi- 70 75

cient pressure to retain the shaft and shutters in the positions to which they are manually adjusted.

Not only is the above described construction self-contained as to all its instrumentalities and controls, thus avoiding the installation of instruments and devices at some distance from the ventilator with pneumatic, electrical or other connections between the same, but by reason of the passage of a continuous small stream of recirculated air over the damper controlling mechanism, a more accurate and satisfactory regulation of the air discharged by the ventilator into the room is secured and the liability of improper conditioning by reason of stagnated air or local currents at the particular location where the control instrument is placed is avoided. The mechanical connections between the damper and its controlling mechanism are accurate and positive, and being all located within the casing, are protected from accidental injury or derangement.

The small continuous flowing stream of recirculated air is of such relatively small magnitude compared with the stream supplied by the fresh air inlet that even when the main recirculating inlet is closed and all the air is taken from the fresh air inlet, there is no appreciable effect upon the condition of the discharged air due to the addition of the small recirculated stream.

While the present invention has been shown and described in what is now considered to be its preferred form, it is to be understood that it may be embodied in other constructions and arrangements.

Having thus described the invention, what is claimed is:

1. A unit heating ventilator comprising a casing provided with a plurality of air inlets and an air outlet, one of the inlets admitting re-circulated air at all times to the casing, a heating element, a fan for creating a flow of air through the inlets and the outlet, and devices located in the air stream entering said re-circulated air inlet for controlling the temperature of the air stream discharged from the outlet independently of the flow of air through another of the air inlets.

2. A unit heating ventilator comprising a casing provided with a fresh air inlet and a re-circulating air inlet which admits re-circulated air to the casing at all times, an air outlet, a heating element, a thermo-regulator controlled by the temperature of the re-circulated air entering the inlet, and devices actuated by the regulator for varying the heating effect of the heating element independent of the flow of air through the fresh air inlet.

3. A unit heating ventilator comprising a casing provided with a fresh air inlet and a main and supplementary re-circulating air inlet, an air outlet, means for controlling the flow of air through the fresh air and the main re-circulating inlets, a heating element, means for creating a flow of air through the inlets and the outlet, and devices located within the casing and exposed solely to the stream of air entering the supplementary air inlet for controlling the temperature of air emitted by the ventilator independently of the flow of air through the fresh air and the main recirculating inlets.

4. A unit heating ventilator comprising a casing provided with a plurality of air inlets and an air outlet, a motor and fan for causing the

flow of air through the casing, a heating element in the casing with an air passage at the side thereof, a shutter for controlling the flow of air over the heating element and through the air passage, and a thermo-regulator located within the casing and exposed to the air stream of the air inlets only for actuating the shutter to differentially by-pass the air around the heating element for controlling the temperature of air emitted by the ventilator.

5. A unit heating ventilator comprising a casing provided with an air inlet and an air outlet, a motor and fan, a heating element an auxiliary air inlet, a supplementary chamber within the casing through which chamber the air from the auxiliary air inlet passes, a thermo-regulator located in the chamber and exposed solely to the air entering the auxiliary air inlet, and means actuated by the regulator to control the temperature of the air discharged by the ventilator independently of the flow of air through the first mentioned air inlet.

6. A unit heating ventilator comprising a casing provided with a main air inlet and a supplementary air inlet which admits recirculated air to the casing at all times and with an air outlet, a heating element, means for controlling the heating effect thereof independently of the flow of air through the main air inlet, devices within the casing and exposed to the recirculated air stream and responsive to the temperature thereof, and positively acting connections between said devices and said means whereby the heating effect of the heating element is varied with variations in the temperature of the stream of recirculated air.

7. A unit heating ventilator comprising a casing having main fresh air and recirculating air inlets, and a small supplementary recirculated air inlet, the volume of air admitted by such supplementary air inlet being insufficient to have appreciable effect upon the temperature of the air admitted by the main air inlet when united therewith, an air outlet, means for controlling the flow of air through the main inlets, a heating element, means for creating a flow of air through the main and supplementary inlets and outlet, and devices carried by the casing and exposed solely to the stream of air entering the supplementary air inlet for controlling the temperature of the air discharged from the outlet.

8. A unit heating ventilator comprising a casing having a main air inlet and a supplementary recirculated air inlet, a heating element, an air outlet, a pair of fans for creating a flow of air through the main and supplementary inlets and outlet, one fan handling the entire volume of air entering the supplementary air inlet and the other fan handling exclusively the air entering the main air inlet, and devices carried by the casing and exposed solely to the stream of air entering the supplementary air inlet for controlling the temperature of the air discharged from the outlet.

9. Apparatus for conditioning air comprising a casing provided with a plurality of main air inlets and a supplementary recirculated air inlet, means for selectively controlling the main air inlets, an air outlet, a conditioning element, means for creating a flow of air through the main and supplementary inlets and outlet, and devices located within the casing and exposed solely to the stream of air entering the supplementary air inlet for controlling the operation of the conditioning element in accordance with the condition

of the air entering the supplementary air inlet.

10. Apparatus for conditioning air comprising a casing having a main air inlet and a supplementary recirculated air inlet, an air outlet, a conditioning element, means operating upon separate streams of air for creating a flow of air through the main and supplementary inlets and outlet, the casing being formed with air passages to conduct the entire volume of recirculated air

10 entering through the supplementary air inlet into one of said separate streams, and devices carried by the casing and exposed solely to the stream of recirculated air entering through the supplementary air inlet for controlling the condition of the air discharged from the outlet.

11. A unit heating ventilator comprising a cas-

ing having main fresh air and recirculating air inlets and a small supplementary recirculated air inlet, an air outlet, a double intake fan for creating a flow of air through the main and supplementary inlets and outlet, the casing being formed with air passages to direct the entire volume of air entering the supplementary air inlet to one fan intake and only air entering a main air inlet to the other fan intake, a heating element, and devices carried by the casing and exposed solely to the stream of air entering the supplementary air inlet for controlling the temperature of the air discharged from the outlet in accordance with the temperature of the air entering the supplementary inlet.
